UNITED STATES PATENT OFFICE.

EVERETT H. CONVERSE, OF BROOKLYN, NEW YORK.

DESIGN FOR A SAMPLE OR PATTERN CARD.

SPECIFICATION forming part of Design No. 17,386, dated June 14, 1887.

Application filed April 6, 1887. Serial No. 233,937. Term of patent 14 years.

To all whom it may concern:

Be it known that I, EVERETT H. CONVERSE, of Brooklyn, in the county of Kings and State of New York, have originated and produced 5 a new and Improved Design for Sample or Pattern Cards, of which the following is a specification.

My design for a sample or pattern card consists of a card having ornamental strips arranged radially to form two reversed and separated segments of a circle, and a sheet or overlapping sheets arranged between such reversed segments.

The accompanying drawing represents a 15 sample or pattern card of my design.

The card, which usually comprises leaves or members A A B, may be made to fold on the dotted lines x x.

The design consists of a card having the ornamental strips C, which are arranged in the 20 reversed but separated arcs or segments of a circle, the strips of each segment radiating from a common center; and I have shown the strips as having a true taper in their width

from their outer ends, or cut in the form of 25 truncated wedges, the narrower ends of which are nearest the center from which the members radiate. These strips substantially cover the segment of the circle in which they are arranged. The strips forming the reversed 30 but separated segments are on the leaves A A, which are separated by the leaf B, and on the leaf B is an ornamental sheet, D; or two or more such sheets, D, may be arranged so as to overlap one another, as clearly shown. 35

What I claim, and desire to secure by Letters Patent, is—

The design for a sample or pattern card, consisting of a card having ornamental strips arranged radially to form two reversed and 40 separated segments of a circle, and a sheet or overlapping sheets arranged between such reversed segments, substantially as herein described.

EVERETT H. CONVERSE.
